Solomon C. Spring

SOLOMON C. SPRING, OF BRISTOL, CONNECTICUT, ASSIGNOR TO
WELCH, SPRING, AND COMPANY, OF SAME PLACE.

Design No. 3,253, dated November 17, 1868.

DESIGN FOR A CLOCK-CASE.

The Schedule referred to in these Letters Patent and making part of the same.

To all whom it may concern:

Be it known that I, SOLOMON C. SPRING, of Bristol, in the county of Hartford, and State of Connecticut, have invented or produced a new and original Design for a Clock-Case; and I do hereby declare that the following is a full, clear, and exact description thereof, which will enable others skilled in the art to make and use the same, reference being had to the accompanying drawings, making a part of this specification, which drawings are a front elevation of my invention or production.

Similar letters of reference indicate like parts.

My invention relates only to the top of the front of a clock-case; and consists of four parts of an octagon for forming the top; combined with a circular sash around the dial.

aa designate the two centre pieces, which are each

one-eighth of an octagon. *cc* designate the other two pieces, which are shorter than one-eighth of an octagon, or shorter than the pieces *aa*. Thus, when the whole are secured together, they do not form quite one-half of an octagon, although the angles, 1, 2, 3, are the same as they would be in an octagon.

The circular sash *A*, around the dial, is set with its centre a little below the ends of pieces *cc*.

What I claim as new, and desire to secure by Letters Patent, is—

The design for a clock-case front, as herein illustrated and described.

SOLOMON C. SPRING.
